UNITED STATES PATENT OFFICE.

DAVID D. GOOD, OF PHILADELPHIA, PENNSYLVANIA.

ADJUSTABLE CLOSET-ROD.

1,266,677.

Specification of Letters Patent. Patented May 21, 1918.

Application filed September 8, 1914. Serial No. 860,652.

To all whom it may concern:

Be it known that I, DAVID D. GOOD, a citizen of the United States, residing at 6203^b Jefferson street, in the city of Philadelphia and State of Pennsylvania, have invented certain new and useful Improvements in Adjustable Closet-Rods, of which the following is a specification, reference being had therein to the accompanying 10 drawing.

My invention has relation to closet rods wherein they are adjustable to different sizes of closets, being supported by plates attached to the opposite wall.

15 My invention has for its object the provision of an adjustable rod for the support of clothes hangers.

20 My invention consists in the novel construction, combination and arrangements of parts hereinafter described.

Throughout the accompanying drawing similar figures indicate similar parts.

Figure 1 represents a perspective view of the entire mechanism.

25 Fig. 2 is a sectional view through the rod 1' on the line X, Y.

Fig. 3 is a side elevation of the supported ends of the rods.

30 Fig. 4 is a top plan view of the supporting plates.

The rods 1 and 1' and the plates 2 and 2' are similar.

In Fig. 1, 2 and 2' are supporting plates designed to be attached to the end walls of 35 a closet by means of screws through the holes 7-7-7. A supporting lug; consisting of the lower horizontal member 6, the inclined member 4 and the top horizontal catch 5; is formed from or attached to the 40 plate. A vertical leaf 9 is placed to stand at an acute angle from the plate 2, its outside vertical edge being distant from the supporting lug 4 the thickness of the rod 1.

45 1 and 1' are flat metal rods having a tang 17 so formed on one end that it stands at a right angle with the vertical plane of the rod and inclines at an acute angle to the horizontal plane of the rod. This tang is 50 a trifle longer than the width of the supporting lug 4.

The opposite ends of the rods 1 and 1' are folded on themselves along a line 18 forming a 45° angle with the lower edge, the folded member being bent upward to

the vertical 19 then across the top edge of 55 the rod 1 to the horizontal 20 then downward to the vertical leaving sufficient space between the back of the rod 1' and the inside face of the last named vertical member 21 to embrace the rod 1.

60

Operation:—The plates 2 and 2' are attached to the opposite walls of a closet by means of screws or nails through the holes 7-7. The rods 1 and 1' are taken one in each hand, the tangs 17 are placed back of 65 the supporting lugs and the flat of the rod between them and the vertical leaves 9 the inwardly extending ends of the rods are raised sufficiently above the supporting plates to allow the tangs 17 to pass down 70 behind the catch 5.

The rods are then lowered to the horizontal when each of the hooked ends consisting of the members 19, 20 and 21 will engage the other rod. As the rods approach the 75 horizontal the upper edge of the inclined tangs 17, on account of their inclination to the rod will be drawn under the horizontal catch 5 of the supporting lug, upward displacement being thus prevented. The edge 80 of the leaves 9 bear against the plane side of the rod securing the tangs 17 in the supporting lugs and hold the rods securely on their edges, the whole making a firm, adjustable support for clothes hangers and 85 the like.

Having thus described my invention I claim:

1. In an adjustable closet rod the combination of supporting plates, supporting 90 lugs thereon; consisting of a horizontal base a sloping face a horizontal catch; and flat rods with inclined rectilinear tangs engageable by the said lugs and catches substantially as described.

95

2. In an adjustable closet rod the combination of supporting plates supporting lugs, horizontal catches thereon and vertical leaves the edges of which are adapted to bear against and secure in place flat metal 100 rods with inclined rectilinear tangs as described.

3. In an adjustable closet rod, the combination of two rods, locking means of support at their outer ends and their hooked inner ends adapted each to engage the opposite rod as they are both brought to the horizontal, substantially as described.

105

4. In an adjustable closet rod the combination of two flat rods, their rectilinear hooks each adapted to engage the opposite rod when brought to the horizontal, inclined rectilinear supporting tangs engageable by supporting lugs and horizontal catches adapted to secure them in place
- 5

when the two rods are brought together in a horizontal position as herein described.

DAVID D. GOOD.
